UNITED STATES PATENT OFFICE.

VICTOR E. EDWARDS, OF WORCESTER, MASSACHUSETTS, ASSIGNOR TO THE MORGAN CONSTRUCTION COMPANY, OF SAME PLACE.

COOLING-BED FOR BAND-IRON.

SPECIFICATION forming part of Letters Patent No. 614,202, dated November 15, 1898.

Application filed July 26, 1897. Serial No. 646,052. (No model.)

To all whom it may concern:

Be it known that I, VICTOR E. EDWARDS, a citizen of the United States, residing at Worcester, in the county of Worcester and 5 State of Massachusetts, have invented a new and useful Improvement in Cooling-Beds for Band-Iron, of which the following is a specification, accompanied by drawings forming a part of the same, in which—

10 Figure 1 represents a side elevation of a cooling-bed for band-iron embodying my invention; and Fig. 2 is a vertical sectional view on line 2 2, Fig. 1.

Similar letters refer to similar parts in both 15 figures.

My present invention relates to an apparatus for cutting a continuous strip of band-iron while it is being delivered from the reducing-rolls into determinate lengths while 20 still in motion, straightening the severed pieces, bringing their ends against a stop-plate, and conveying the strips to a common pile or receptacle, said apparatus being capable of acting upon the strips of band-iron 25 while they are still in motion, thereby enabling the operations to be carried on during the process of cooling; and these objects are accomplished by means of the mechanism shown in the accompanying drawings and 30 hereinafter described, the several features of novelty being specifically set forth in the annexed claims.

Referring to the drawings, A A' denote a pair of feed-rolls by which a strip of band-iron B as delivered from the last pair of reducing-rolls is fed forward at a speed independently of the speed of the reducing-rolls. Shear-blades A² A² are inserted in the periphery of the rolls A A' parallel with their axes 40 and arranged to act conjointly in severing the band-iron as the rolls are rotated in the direction of the arrows 1 1, severing the band-iron once during each revolution of the rolls A A' into lengths equal to the periphery of the 45 rolls. The peripheries of the rolls A A' are concentric with their axes of rotation and are arranged to run in contact with the strip of band-iron, so that the rolls A A' are primarily feed-rolls, thereby imparting a momentum to 50 the strip of band-iron. The momentum of the severed pieces is sufficient to carry them

forward through a guide-trough C upon a cooling-bed C', having its upper surface C² inclined and located slightly below the guide-trough C, so that the band-iron as it passes 55 out of the guide-trough C upon the inclined surface C² is bent downwardly by its own weight, as represented at B', Fig. 1. Re-cessed in the cooling-bed C' is a semicircular rocking shaft D, having its plane side D' co- 60 incident with the inclined surface C² at one end by its rocking motion, but being slightly raised above the inclined surface C² at the opposite end of its rocking motion, as represented in Fig. 2, that portion of the curved 65 periphery of the shaft D which is raised above the inclined surface C² forming a stop to prevent the band-iron from sliding down the inclined surface C². The side of the rocking shaft B which forms the stop for the band-iron is located at a lower point upon the inclined surface C² than the guide-trough C, so 70 the heated band-iron becomes deflected in the direction of its width, as shown at B², Fig. 2.

The severed strips of band-iron are straight- 75 ened by their contact with the inclined surface C² and by the side of the rocking shaft D. At the end of the cooling-bed C' opposite the guide-trough C is a stop-plate E, against which the successive pieces are brought in 80 order to even their ends. As the heated and flexible pieces of band-iron are projected upon the inclined surface C² with consider- 85 able velocity it becomes necessary to retard their advance movement in order to prevent them from being carried forcibly against the stop-plate E, which would cause the strip of band-iron to bend or buckle. This is accom- 90 plished by means of a brake-shoe F, carried by a two-armed lever F', pivoted to the rigid framework of the machine and connected by a link F² with a crank-pin F³, which is adjustable in a slotted face-plate F⁴, carried on the shaft of the upper feed-roll A. The 95 brake-shoe affords sufficient frictional resistance to retard the forward movement of the severed strip B³, but not enough to entirely check its motion. As the last end of the severed strip B³ passes through the guide-trough C it drops down upon the inclined surface C² 100 and against the raised edge of the rocking shaft D and below the path of the advancing

end of the next succeeding strip, so that as the next strip is projected forward at a higher rate of speed than the next preceding strip it will pass over the rear end of the latter and 5 avoid a conflict between the two strips.

When the severed strip of band-iron has been completely delivered upon the inclined surface C^2 , the shaft D is rocked to bring its plane surface D' coincident with the inclined 10 surface C^2 and allow the strip of band-iron to slide down the inclined surface C^2 and be supported upon the peripheries of a series of 15 conical feed-rolls G, which project through openings G^2 in the inclined surface C^2 . The rolls G rotate in the direction of the arrows 2, Fig. 1, in order to move the strips of band-iron forward against the stop-plate E. The rolls G are conical, so that the forward or 20 feeding motion of the strips becomes gradually reduced in speed as they approach the lower ends of the rolls in order that they may not be carried violently against the stop-plate E. Each strip of band-iron as it slides off 25 the rolls G is delivered upon an endless apron H, carried upon rolls H^2 H' , having parallel axes. The apron H throughout the upper portion of its travel is supported upon a platform I in order to maintain the apron in a horizontal plane. The shaft D is rocked by 30 means of an arm J projecting from one end of the shaft and operatively connected by means of links J^1 J^2 and a walking-beam J^3 with a crank-pin J^4 , adjustably held in a slotted face-plate J^5 , attached to the shaft of the 35 lower feed-rolls A ^{2} . I do not, however, confine myself to the specific mechanism shown for imparting a rocking motion to the brake-shoe F or the rocking shaft D.

The operation of the apparatus above described is as follows: A continuous strip of heated band-iron as delivered from the reducing-rolls is conducted between the revolving feed-rolls A A', by which it is projected forward through the guide-trough C and is 40 severed at each revolution of the rolls A A' by means of the shear-blades A ^{2} . The momentum of the strip after it has been severed by the shear-blades is sufficient to carry it forward upon the inclined surface C^2 , its 45 flexibility allowing its weight to carry it downward into the corner formed by the inclined surface C^2 and the raised edge of the semicircular rocking shaft D, causing the heated strip to be straightened both in the plane of its thickness and the plane of its width. At 50 the proper period the motion of the severed strip is retarded and prevented from coming in contact with the stop-plate E by means of the brake-shoe F, the movement of the band-iron, however, being allowed to carry the rear end out of the guide-trough C upon the inclined surface C^2 . The shaft D is then 55 rocked to allow the severed strip to slide down the inclined surface and be supported by the periphery of the conical rolls G, which are rotated by connected driving mechanism to move the strip forward toward the stop-

plate E with a gradually-retarded movement as the band-iron approaches the smaller end of the conical rolls, from which it is carried 70 forward by the apron H and delivered upon a common pile or into a receptacle.

What I claim as my invention, and desire to secure by Letters Patent, is—

1. The combination of a bed to receive the 75 severed strips, a pair of feed-rolls running in contact with the strip of band-iron by which the strip of band-iron is projected forward, and cooperating shear-blades carried by said feed-rolls for severing the strip of band-iron 80 while it is being fed forward by the action of said feed-rolls, whereby momentum is imparted sufficient to carry the severed strip upon the bed, substantially as described.

2. The combination of a pair of rotating 85 shear-blades, a pair of feed-rolls running in contact with the strip of band-iron and having their axes coincident with the axes of said shear-blades, whereby momentum is imparted to the strip of band-iron sufficient to 90 carry the severed strips forward upon a receiving-bed, and a receiving-bed located below the plane of cutting, whereby the severed strip is carried downward by gravity below the path of the next succeeding strip, sub- 95 stantially as described.

3. The combination with a bed and a feeding mechanism by which a strip of band-iron is projected upon said bed, of a frictional 100 brake whereby the velocity of the strip is retarded in its movement on said bed, substantially as described.

4. The combination with a bed and feeding mechanism by which a strip of band-iron is projected on said bed, of a frictional brake 105 whereby the velocity of the strip is retarded in its movement on said bed and means for removing said brake from contact with the strip, substantially as described.

5. The combination of a bed, a feeding mechanism, a cutting mechanism interposed between said feeding mechanism and said bed and a guide by which the severed strip is guided from said cutting mechanism upon 110 said bed, said guide being located in the plane of the cutting mechanism and above the plane 115 of the bed, substantially as described.

6. The combination of a cutting mechanism, a feeding mechanism whereby a momentum is imparted to the strip of band-iron, 120 a laterally-inclined bed upon which the severed strip is moved sidewise by gravity, a removable barrier arranged lengthwise said inclined bed and having a straight edge adapted to serve as a guide for the advancing end of 125 the severed strip, substantially as described.

7. The combination of a feeding mechanism, a cutting mechanism, an inclined bed upon which the severed strip is projected directly from said cutting mechanism, and a barrier by which the strips are held from sliding on said bed by gravity, said barrier being located in a lower plane than that in which the strips are fed on said bed, whereby the 130

advancing end of the strip, as it is delivered from the feeding mechanism, is moved by gravity on the surface of said bed and carried into contact with said barrier, substantially as described.

8. The combination of an inclined bed, a feeding mechanism by which the severed strip is projected upon said bed, a rocking barrier consisting of a semicircular shaft recessed in said bed and having its axis of rotation parallel with the line of motion of the severed strip and means for intermittently rocking said shaft and releasing the strip, substantially as described.

15 9. The combination of an inclined bed, a feeding mechanism, a cutting mechanism, a removable barrier by which the severed strip is held from sliding down said inclined bed and means for moving said barrier in correspondence with the action of said cutting mechanism, whereby the movement of said barrier to release the severed strip is determined by the action of said cutting mechanism, substantially as described.

25 10. The combination of an inclined bed, a cutting mechanism, a brake by which a frictional resistance is applied to the severed strip and means for actuating said brake in correspondence with the action of said feeding mechanism, substantially as described.

35 11. The combination of an inclined bed, a cutting mechanism, a movable barrier by which the severed strip is held from sliding down said inclined bed, a brake by which a frictional resistance is applied to check the longitudinal movement of the severed strip, an actuating mechanism by which said brake, said movable barrier and said cutting mechanism are moved in correspondence with each 40 other, substantially as described.

45 12. The combination with an inclined bed of a series of rolls upon which the severed strip is delivered and by which a longitudinal movement is given to the strip and a stop-plate by which the longitudinal movement of the strip is limited, substantially as described.

13. The combination with a bed to receive the severed strip, of a series of conical rolls by which the strip is moved longitudinally

and means whereby the strip is moved sideways from the larger to the smaller ends of said conical rolls whereby the velocity of the strip is gradually retarded, substantially as described.

14. The combination of an inclined bed to receive the severed strip, a removable barrier having a continuous straight edge by which the strip is straightened, and a series of rotating rolls upon which the severed strip is delivered by gravity by the removal of said barrier, said rolls being arranged to impart a longitudinal movement to the severed strip, substantially as described.

15. The combination of a series of rolls to receive the severed strips having their supporting-surfaces inclined whereby the strips are moved sideways by gravity, means for rotating said rolls by which a longitudinal movement is given to the severed strips during their sidewise movement and a stop-plate by which the longitudinal movement of the strip is limited, substantially as described.

16. The combination of an inclined bed to receive the severed strip and means for moving the severed strip longitudinally with a gradually-retarded velocity during the process of cooling, substantially as described.

17. The combination of an inclined bed to receive the severed strip, means for moving the strip longitudinally on said bed with a gradually-retarded motion during the process of cooling and a stop by which the movement of the strip is limited, substantially as described.

18. The combination of an inclined bed upon which the severed strip is moved by gravity upon a series of conical rolls, conical rolls by which the strip is moved longitudinally with a gradually-retarded velocity, a stop by which the longitudinal movement of the strip is limited and a movable conveyer upon which the strip is delivered from said conical rolls, substantially as described.

Dated this 10th day of July, 1897.
